UNITED STATES PATENT OFFICE.

CARL CHRISTENSEN, OF BRADLEY, ILLINOIS, AND CHARLES W. NOONEN, OF COUNCIL BLUFFS, IOWA, ASSIGNEES TO DAVID BRADLEY MANUFACTURING COMPANY, OF BRADLEY, ILLINOIS, A CORPORATION OF ILLINOIS.

NECK-YOKE.

No. 911,112.

Specification of Letters Patent.

Patented Feb. 2, 1909.

Application filed October 26, 1907. Serial No. 399,278.

To all whom it may concern:

Be it known that we, CARL CHRISTENSEN and CHARLES W. NOONEN, citizens of the United States, and residing at Bradley, in the 5 county of Kankakee and State of Illinois, and at Council Bluffs, in the county of Pottawattamie and State of Iowa, respectively, have invented certain new and useful Improvements in Neck-Yokes, of which the following is a specification, reference being had 10 to the accompanying drawings.

Our invention relates to neck yokes, and has for its object to provide a new and improved neck-yoke for use with four-horse 15 teams. We accomplish this object as illustrated in the drawings and as hereinafter described.

That which we believe to be new is set forth in the claims.

20 In the drawings,—Figure 1 is a plan view of our improved neck-yoke, showing also the forward ends of two poles or tongues, such, for example, as those commonly employed for double-row cultivators; and Fig. 2 is a 25 sectional view on line 2—2 of Fig. 1.

Referring to the drawings,—3—4 indicate the poles or tongues, which extend forward from the machine frame in the usual way.

5 indicates a crossbar extending across the 30 front ends of the poles 3—4 and rigidly connected therewith by straps 6, as shown.

7 indicates an equalizer comprising a bar, which extends across the poles 3—4, its ends 35 pivotally supporting yokes 8—9 at opposite sides of the poles 3—4, respectively, said yokes being so placed as to be in proper position for convenient attachment of two horses to the ends thereof, two horses being placed at the left-hand side of pole 3, as shown in 40 Fig. 1, and two at the right-hand side of pole 4.

10—11 indicate rods, the outer end portions of which are connected with the end portions of the equalizer 7, the inner end portions 45 extending to the center of said equalizer and provided with loops 12—13, respectively, which are adapted to receive a clevis or coupling 14 pivoted to the crossbar 5, as shown in Fig. 1. By this construction the 50 rods 10—11 serve to suspend the neck-yoke when not in use and also act to hold it in place when in use. The arrangement is such

that when the neck-yoke is in use it may be swung backward and upward under the forward ends of the poles 3—4, against which it 55 bears, so that it serves to support the weight of the poles. When not in use the neck-yoke hangs suspended from the coupling 14, as shown in dotted lines in Fig. 1. The yokes 8—9 are connected with the end portions of 60 the equalizer 7 by links 15—16 placed centrally of said yokes, so that the weight of the poles is equally distributed between the four horses.

That which we claim as our invention, and 65 desire to secure by Letters Patent, is,—

1. In a four-horse neck-yoke, the combination of a pair of poles, and an equalizer pivotally supported at the forward end portions of said poles and arranged to be moved 70 upward under the forward ends of said poles to support the same, and means for attaching the horses to said equalizer.

2. In a four-horse neck-yoke, the combination of a pair of poles, an equalizer pivotally supported at the forward end portions of said poles and arranged to be moved upward under the forward ends of said poles to support the same, and yokes connected with 75 the outer end portions of said equalizer.

3. In a four-horse neck-yoke, the combination of a pair of poles, a crossbar connected with the forward ends thereof, an equalizer extending across said poles at the under side thereof, means pivotally suspending 85 said equalizer from said crossbar, and yokes carried at the ends of said crossbar.

4. In a four-horse neck-yoke, the combination of poles, a crossbar connecting the forward end portions thereof, an equalizer 90 extending across said poles at the under side thereof and being arranged to be moved upward into engagement therewith so as to support the poles when the neck-yoke is in use, and yokes at the ends of said equalizer. 95

CARL CHRISTENSEN.

CHARLES W. NOONEN.
